UNITED STATES PATENT OFFICE.

FREDERICK J. DROEGE, OF COVINGTON, KENTUCKY.

APPARATUS FOR CASTING STEEL INGOTS.

1,299,148.

Specification of Letters Patent.

Patented Apr. 1, 1919.

Application filed December 24, 1917. Serial No. 208,587.

To all whom it may concern:

Be it known that I, FREDERICK J. DROEGE, a citizen of the United States, and a resident of Covington, in the county of Kenton and State of Kentucky, have invented certain new and useful Improvements in Apparatus for Casting Steel Ingots, of which the following is a full, clear, and exact description, reference being had to the accompanying drawing, forming part of this specification.

In the ordinary and commercial method of casting steel ingots, upright cast iron molds are employed, arranged in a row and resting on a base plate or slab called the "stool." The molten steel is then poured into the molds from the top. With this method, the steel cools first at the bottom and there is a tendency for the lower portion to draw away, as it were from the top portion of the ingot, piping of the metal is apt to occur and defects in the upper portion of the ingot are frequently the result. A considerable portion of each ingot has therefore to be cut off and returned to scrap for remelting.

It has also been customary to connect the molds by gates in the stool and to allow the metal to flow into the molds from the bottom.

This method of pouring from the bottom does not overcome the defects, because there is still too great a difference in the cooling of the ingot in view of its length. I have discovered, however, that by providing a fire clay bottom for the lower portion of the mold, utilizing from fifteen to twenty per cent. of the length of the mold for this purpose, I am able to pour the metal either from the top or bottom of the mold with equally good results and that with this method and the construction of molds to be hereinafter particularly pointed out and claimed, I am able to prevent "piping" and that the percentage of loss in casting is reduced to a minimum.

In the drawing,

Figure 1 is a perspective view of my improved molding apparatus, showing one of the cast iron molds in dotted outline.

Fig. 2 is a plan of the base plate, with one of the molds in place.

Fig. 3 is a vertical cross section taken on the line 3—3 of Fig. 2.

Fig. 4 is a cross section on the line 4—4 of Fig. 2.

Fig. 5 is a perspective view of one of the gates between the molds.

I have illustrated in the drawing three molds for casting three steel ingots; but of course it will be understood that as many molds arranged in series as may be desired may be employed.

The bottom plate or stool 1, which is usually a cast iron plate, is formed with a series of central depressions 2, 2, connected by passages 3, 3, which I prefer to form alternately at opposite sides. To form the lower portion of the ingot molds, I line the bottom and sides of the depressions with fire clay brick 4, or other suitable refractory material, and as illustrated in the drawing I employ from fifteen to twenty per cent. of the length of the mold for this purpose, leaving a passage into each mold near the bottom, and fire clay gates 5, 5, with a passage 6 therethrough to register with the opening into the molds, are placed in the bottom of the passages between the depressions. The fire clay lining of the depressions in the stool comes flush with the top surfaces of the stool and forms the lower portions of the molds. Upon these fire clay portions are located the cast iron molds 7, 7. The lining of the refractory material is preferably about two inches thick and the cast iron molds are preferably about four inches thick so that the cast iron molds when located rest partly on the fire clay lining and partly on the stool as shown in Fig. 3. The gates 5 are then placed between the molds and the space above the gates is filled in with refractory material flush with the surface of the plate.

The metal is poured in the usual way into the top of the central mold, and the molten metal flows through the gates or passageways 6, filling up the outer molds from the bottom and the middle mold from the top. All of the molds, however, have their lower portions located in their respective depressions in the stool of fire clay or refractory material. When the metal has been poured, and has cooled sufficiently though while still hot, a crane grabs the molds by gripping the handles 8, and they are then lifted off of the ingots, leaving the ingots upright in the fire clay lower portion. The jarring of the molds by striking them or rocking them slightly to separate the molds from the ingots usually jars the ingots sufficiently to fracture the web of metal connecting the in-

gots through the gates at the bottom, and the ingots can then be lifted out of the fire clay portion. In order to separate the ingots, however, in the event that they are not 5 broken apart, I form a narrow transverse slot 9, 9, between each mold so that they may be sawed apart.

By thus providing a fire clay or refractory material for the lower portion of the mold, 10 I have discovered that the usual "piping" of the ingot is almost entirely obviated, and the ingots are solid and uniform throughout their entire length. The heat is retained by the fire clay permitting the molten material 15 to consolidate more effectively than results when the cast iron mold extends to the bottom of the mold.

Having thus described my invention, what I claim as new and desire to secure by 20 Letters Patent, is:—

1. In an apparatus of the kind specified, the combination with a bed plate, provided with a series of sockets to form a part of the mold and lined with fire clay or other 25 refractory material, of ingot molds vertically arranged and mounted on said refractory material, the refractory base portion forming a substantial continuation of the ingot molds of fifteen to twenty per cent. 30 of the length of the mold, and gates connecting adjacent molds with each other near the bottom whereby a plurality of molds may be filled from a central mold.

2. In an apparatus of the kind specified, 35 the combination with a bed plate, provided with a series of sockets to form a part of the

mold and lined with fire clay or other refractory material, with a series of passages connecting adjacent sockets of ingot molds vertically arranged and mounted on said refractory material and supported by the bed plate, the refractory base portion forming a substantial continuation of the ingot molds of fifteen to twenty per cent. of the length 40 of the mold, and gates in the passageways connecting adjacent molds near the bottom with each other whereby a plurality of molds may be filled from a central mold. 45

3. In an apparatus of the kind specified, the combination with a plurality of cast 50 metal molds open at both ends, with extensions therefor of refractory material forming the lower portion and bottom of the molds, with passages between adjacent molds near the bottom, one of the cast metal 55 molds serving as a gate for filling the adjoining molds.

4. In an apparatus of the kind specified, the combination with a bed plate, provided with a series of depressions lined with fire 60 clay or other refractory material, of ingot molds vertically arranged and mounted on said refractory material, the refractory bed portion forming a continuation of the ingot molds, and gates connecting adjacent molds 65 near the bottom with each other whereby a plurality of molds may be filled from a central mold, with transverse slots in the bed plate for severing the ingots from each other before removal from the bed plate.

FREDERICK J. DROEGE.
